UNITED STATES PATENT OFFICE

HAVELOCK TREVORROW, OF BIRMINGHAM, ENGLAND

APPARATUS FOR THE DIPPING OF TUBES OR RODS FOR PICKLING, ETC.

Application filed April 29, 1929, Serial No. 359,086, and in Great Britain May 10, 1928.

In the manufacture of steel and other metal tubes or rods, it is necessary for pickling, cleaning, galvanizing, lubricating and other purposes to dip such work into acid or other liquids for effecting the required treatment. Such liquids are contained in vats, baths, troughs or like receptacles in association with which work supports in the form of looped chains have been arranged with means for so moving said chains as to effect the dipping of the work, which is inserted endwise into the loops of said chains.

The object of this invention is to provide means for effecting the said dipping in a more convenient, economical and efficient manner.

In accordance with the invention, the work to be dipped is supported in one or more flexible slings having open sides, permitting of the front or lateral insertion and withdrawal of the work. These slings comprise chains or other flexible members which are attached at one end of each to one side of the tank which contains the pickling or other bath. The other end of each sling extends upwardly above the opposite side of the tank, so that, upon lowering the same, the intermediate portion of the sling descends in a loop into the bath. When the free ends of the slings are raised and lowered, the other ends being fixed, the work-pieces in the slings, such as tubes or rods, will be caused to roll or move laterally with respect to each other. I make use of this action, caused by the described arrangement of the slings, to obtain the desired "tumbling" of the work-pieces in the pickling solution, necessary for the removal of scale.

In accordance with my improved method, the work-pieces are lowered into and raised from the bath by lowering and raising the free ends of slings arranged as described, with the work-pieces carried by the slings, and tumbling of the work is accomplished by repeatedly raising and lowering the free ends of the slings during the continuance of the dipping process.

It is highly desirable that the solution should be drained from the work-pieces, particularly in the case of tubes, when the work

is removed at the end of the dipping process. This is accomplished by me, as one feature of my improved method, by raising the sling at one end of the work-pieces faster than the sling at the other end, or by raising one sling to a higher level than the other, at the termination of the dipping, so that the work-pieces will be tilted lengthwise, as they are lifted from the bath prior to removal from the slings. They may, of course, be given such tilting movements during all of their rising and falling movements with the slings, the essential point being that they be given such tilting movement just prior to their removal from the slings.

The invention also comprises improved means whereby the described method may be practiced, the mechanism including means, preferably automatic, for repeatedly raising and lowering the slings during the continuance of the dipping operation. The improved apparatus also includes means for causing the described tilting of the work-pieces as they are raised, to effect draining.

In order that the invention may be more clearly understood, attention is directed to the accompanying drawings, illustrating one embodiment of apparatus comprising the invention, and by which the improved method may be practised. In the drawings:

Figure 1 is a front elevation, Figure 2 a plan and Figure 3 an end view of the apparatus constructed in accordance with this invention.

Figure 4 is an end view showing a vertically movable cradle in combination with the dipping slings.

In carrying the invention into effect as shown in Figures 1-3, the flexible slings *a* are formed by a plurality of lengths of chain or rope, one end of each length being anchored to drums *g* on a winding shaft *b* mounted above one side of the dipping trough *c*, and the other end fixed to the opposite side of the trough. The said lengths thus form open sided loops across the trough, and the work, consisting of metal tubes or rods or the like, can be readily in-

serted laterally into the open sides of the versed automatically when the lowermost position of the slings is reached, whereupon the work rises until its original uppermost position is reached, when the operation of the reversing switch again starts the slings downward. The operation is continued as long as desired, when it is stopped by stopping the motor. Each time the work-pieces near their upper most position, the conical drum causes them to be tilted, so that, if the work-pieces are tubes, a flow of liquid therein will be caused, to drain them. The work-pieces may now be removed from the slings, as, for example, by hand.

It should be understood that the invention is not limited to the construction which has been specifically described, by way of example, the scope of the invention being indicated by the appended claims.

Having thus described my invention what I claim as new and desire to secure by Letters Patent is:

1. In apparatus for dipping metal tubes, bars, rods and similar articles in pickling or other baths, the combination of a tank for the bath, rotary means mounted above the tank at one side thereof, flexible slings extending, at one end thereof, over said rotary means and attached at the other end thereof to the opposite side of said tank, means for lowering the first named ends of said slings to lower the intermediate portions thereof into said tank with the work-pieces thereon, and for raising said first-named ends, at the conclusion of the dipping operation, for the removal of the work-pieces, and means for causing the alternate raising and lowering of said first-named sling ends during the continuance of the dipping operation, to cause relative rolling motion of said work-pieces.

2. In apparatus for dipping metal tubes, bars, rods and similar articles in pickling or other baths, the combination of a tank for the bath, rotary means mounted above the tank at one side thereof, flexible slings extending, at one end thereof, over said rotary means and attached at the other end thereof to the opposite side of said tank, means for lowering the first named ends of said slings to lower the intermediate portions thereof into said tank with the work-pieces thereon, and for raising said first-named ends, at the conclusion of the dipping operation, for the removal of the work-pieces, and means for causing the alternate raising and lowering of the said first-named sling ends during the continuance of the dipping operation, to cause relative rolling motion of said work-pieces.

3. In apparatus for dipping metal tubes, bars, rods and similar articles in pickling or other baths, the combination of a tank for the bath, a pair of spaced flexible slings

When it is undesirable to allow the work pieces to roll freely off the guide rails *h*, I may arrange adjacent to the said rails (as shown in Figure 4) a cradle consisting of a plurality of suitably shaped supporting bars *j* which are suspended by ropes or chains *k* connected to coiling drums *l* and guide pulleys *m*. By rotating these drums the cradle can be raised or lowered as required. The dotted lines in Figure 4 show the cradle in the lower position.

55 It will be noted that the operation, as performed with the apparatus specifically described above, is as follows: The work-pieces are placed within the slings when the latter are in their uppermost position, above the level of the bath in the tank or trough *c*, in which position the loops of the slings are sufficiently curved to contain the required number of tubes, rods, or bars. The motor being started, the slings are lowered into the bath, the motion being re-

attached, at one end of each thereof, to one side of said tank and extending upwardly, at the other end of each thereof, above the opposite side of said tank, and means for lowering said last-named sling ends to lower the intermediate portions of the slings into said tank with the work-pieces thereon, and for raising said last-named ends, one more rapidly than the other, at the conclusion of the dipping operation, to effect tilting and draining of the work-pieces, prior to their removal from said slings.

4. In apparatus for dipping metal tubes, bars, rods and similar articles in pickling or other baths, the combination of a tank for the bath, a rotary shaft mounted at one side of said tank, a cylindrical drum and a conical drum on said shaft, and a pair of flexible slings, each attached at one end thereof to the side of said tank opposite to said shaft and attached at their other ends to said cylindrical drum and to said conical drum, respectively.

5. In apparatus for dipping metal tubes, bars, rods and similar articles in pickling or other baths, the combination of a tank, for the bath, a pair of spaced flexible slings attached, at one end of each thereof, to one side of said tank and extending upwardly, at the other end of each thereof, above the opposite side of said tank, said last-named sling ends being lowerable to lower the intermediate sling portions into said tank with the work-pieces therein, means for alternately raising and lowering said last-named sling ends during the continuance of the dipping operation, and means for causing the raising of said last-named sling ends, one more rapidly than the other, at the conclusion of the dipping operation, for the removal of the work-pieces from said slings.

6. In apparatus for dipping metal tubes, bars, rods and similar articles in pickling or other baths, the combination of a tank for the bath, a rotary shaft mounted at one side of said tank, flexible slings attached at one end of each thereof to said shaft and attached at the opposite ends thereof to the opposite side of said tank, the intermediate parts thereof being lowerable into said tank, a motor, connections therefrom for driving said shaft in opposite directions, a switch for reversing said motor, and connections from said shaft to said switch for repeatedly and automatically raising and lowering said first-named sling ends during the dipping operation to cause relative rolling motion between the work-pieces.

In testimony whereof I have signed my name to this specification.

HAVELOCK TREVORROW.
